REFINEMENT OF VITAMIN-CONTAINING
UNSAPOONIFIABLE MATTER OF OILSArchie Black, New Brunswick, N. J., assignor to
E. R. Squibb & Sons, New York, N. Y., a corpora-
tion of New YorkNo Drawing. Application April 22, 1932
Serial No. 606,903

3 Claims. (Cl. 167—81)

This invention relates to the refinement of the vitamin-containing unsaponifiable matter of oils.

In the processes commonly employed, the vitamin-containing unsaponifiable matter of oils is isolated by the successive steps of saponifying the oil, extracting the soap with a solvent in which the unsaponifiable matter dissolves but the soap does not, removing the solvent from the extract by evaporation, and removing most of the cholesterol from the extract by crystallization from a solvent. There remains a semi-solid brown mass, the crude unsaponifiable matter.

It is the object of this invention to provide a simple and efficient method of refining such unsaponifiable matter so as to obtain a product characterized by higher concentration of vitamins and by increased palatability in virtue of superior flavor, odor, and color.

Essentially the method of the invention comprises dissolving the unsaponifiable matter in a substantially oil-immiscible solvent, preferably a solvent selected from the group consisting of alcohol and dioxan; and washing the solution with small portions of an oil, preferably an oil selected from the group consisting of corn, cod-liver, olive and cottonseed oils. Such oil washing, which entails the loss of only a negligible amount of the vitamins, not only eliminates from the unsaponifiable matter a large proportion of the inert substances, but also makes it far more acceptable for human consumption. The small quantity of oil left in the refined unsaponifiable matter may be removed by saponification with an alkali, the vitamins being then extracted from the soap.

As an example, a 60 cc. alcohol solution of the unsaponifiable matter of 2000 g. of cod-liver oil is thoroughly shaken with 5 cc. of corn oil in a separatory flask, the mixture is allowed to stand for about an hour, and the oil layer that has set-

tled to the bottom is drawn off. The alcohol solution is shaken with 5 cc. more of corn oil; after settling, this oil layer is drawn off; and the combined oil fractions are washed with two portions of alcohol, which are then added to the original alcohol solution; and the alcohol is distilled off. The resulting oily residue, after removal of saponifiable oil in the manner already described, weighs only about 40 percent as much as the crude unsaponifiable matter (the rest being in the washings), is much lighter in color and has a markedly better flavor and odor, and is found by biological and color tests to contain about 95 percent of the original vitamins A and D.

It is to be understood that the foregoing embodiment is merely illustrative and by no means limitative of the invention, which may assume various other forms—as to particular substances, proportions, and procedures—within the scope of the appended claims.

I claim:

1. The method of refining the vitamin-containing unsaponifiable matter of oils that comprises dissolving such unsaponifiable matter in a substantially oil-immiscible solvent and washing the solution with small portions of an oil.

2. The method of refining the vitamin-containing unsaponifiable matter of oils that comprises dissolving such unsaponifiable matter in a solvent selected from the group consisting of alcohol and dioxan, and washing the solution with small portions of an oil selected from the group consisting of corn, cod-liver, olive, and cottonseed oils.

3. The method of refining the vitamin-containing unsaponifiable matter of oils that comprises dissolving such unsaponifiable matter in alcohol and washing the solution with small portions of corn oil.
